DESIGN FOR A HAMMER HEAD

Bernard L. McClure, Norwalk, Ohio

Application August 27, 1945, Serial No. 121,673

Term of patent 14 years

(Cl. D93—4)

To all whom it may concern:

Be it known that I, Bernard L. McClure, a citizen of the United States, residing at Norwalk, in the county of Huron and State of Ohio, have invented a new, original, and ornamental Design for a Hammer Head, of which the following is a specification, reference being had to the accompanying drawing, forming part thereof.

The essential feature of my design resides in the portion shown in full lines in the accompanying drawing, of which:

Fig. 1 is a front elevation of a hammer head, showing my new design;

Fig. 2 is a side elevation thereof;

Fig. 3 is a section on the line 3—3 of Fig. 2; and

Fig. 4 is a section on the line 4—4 of Fig. 2.

I claim:

The ornamental design for a hammer head, substantially as shown and described.

BERNARD L. McCLURE.
